UNITED STATES PATENT OFFICE.

KARL WÖRTMANN, OF MUNICH, GERMANY.

COMBINATION LOCK.

Application filed September 12, 1924. Serial No. 737,339.

To all whom it may concern:

Be it known that I, KARL WÖRTMANN, a citizen of the German Republic, residing at Munich, Germany, have invented certain new and useful Improvements in Combination Locks, of which the following is a specification.

This invention relates to a combination lock with several rotatable bolts which are juxtaposed, marked with adjusting signs and designed to secure a locking rod one end of which locks the locking bolt, the other end of said rod forming an adjusting handle.

The invention has for its object on the one hand to simplify the manipulation of the locking bolt by this bolt being automatically rotated into the open position and on the other hand to permit of opening the lock even if the secret number to which the rotatable bolts have been adjusted has been forgotten.

These objects are attained according to the invention by controlling the locking bolt made in one piece by a resilient traction member acting between the two arms of the U-shaped lock bow, said traction member making the locking bolt oscillate in horizontal direction when the same is being released. The heads of the rotatable bolts are round and have each locking pins adapted to be shifted in opposite directions and designed to come in engagement with the caps of the locking bolts, of polygonal cross section and marked with the adjusting signs, when the locking rod is in the open position so that this locking rod can be locked in position with the aid of the signs on the caps.

An embodiment of the invention is shown by way of example on the accompanying drawings, in which:

Fig. 1 is a front elevation.

Fig. 2 shows the head of the rotatable locking bolt with the cap which is shown in section.

Fig. 3 is a section on line A—A of Fig. 1.

Fig. 4 shows the position adopted by the caps of the rotatable bolts at the open position of the lock.

The safety lock which is made in different sizes and especially designed for the locking of bicycles, motorcycles and motor cars consists of a U-shaped bow *a* an opening between the arms of which is adapted to be locked by a bolt *b*. In the lower arm of bow *a* a locking bolt *c* controlled by a

spring *e* is rotatably and shiftably mounted, the rear end of said locking bolt *c* forming an adjusting handle *d* and the front end of the same engaging with an annular groove in the corresponding end of the locking bolt *b*. Over the locking bolt or rod *c* transversely to the same a convenient number of juxtaposed rotatable bolts *f* are arranged which have each an incision designed to engage with the flattened part of the locking rod. The locking rod has annular grooves, one for each rotatable bolt.

The heads *i* of the rotatable bolts *f* bearing against the outer surface of the lower arm of the U-shaped bow *a* are round and covered each by a cap *g* of polygonal, preferably hexagonal cross section. According to the invention each head *i* has a central cross bore *k* in which two locking pins *l* are movably mounted the outer ends of which are conical. Between every two locking pins *l* a spiral spring *m* is located which pushes said locking pins permanently in outward direction so that their conical or pointed ends slide upon the inner surface of the corresponding cap *g*.

The heads *i* of the rotatable bolts *f* project each with an extension through the corresponding cap and have a mark *n* on the outer surface of the extension (Fig. 4). The adjusting head *d* of the locking rod *c* has also a mark *n* on its outer surface. The lock can be opened when all the marks *n* are properly adjusted according to a secret key which is in possession of the proprietor of the lock.

The locking bolt *b* is cylindrical or of angular cross section. Its free end engages with an aperture *o* of the upper arm of the U-shaped bow *a* and bears against an abutment *p*. A rope or chain *q* attached with one end to said locking bolt *b* engages with an angular groove *r* of the upper arm of the U-shaped bow and is with its other end attached to a pull spring *s*. A pin *t* is arranged in the upper arm of the U-shaped bow *a* at a convenient point.

When the rotatable bolts *f* have been adjusted so that the flattened part of the locking bolt *c* coincides with the grooves of the rotatable bolts the lock can be opened by pulling out the locking rod *c*. When the locking bolt *b* has been released by the locking rod *c* the spring *s* begins to act in pulling said locking bolt first in upward direction and making the same then oscillate

through 90° in the aperture o to pull it in the horizontal direction backward so that the locking bolt is parallel with the upper arm of the **U**-shaped bow a as shown in Fig. 5 1 in dash and dot lines. The end of the chain q attached to the locking bolt bears in this position of the locking bolt against the stop pin t so that the locking bolt is stopped. The unlocking of the locking bolt, the pulling 10 of the same in upward direction and the pulling back of the same in horizontal direction which up to the present required three different manipulations is now automatically effected in one single operation.

15 The coupling between the rotatable bolts f , i and the caps g can be effected with the aid of the locking pins l the conical ends of which engage with the corners in the caps so that the elements of the lock can be adjusted to the position in which the corresponding faces of the caps are situated in one plane with the faces of the arms of the **U**-shaped bow even when the secret number of the lock has been forgotten. In such 20 a case the marks n of the rotatable bolts are adjusted by rotating the caps g according to the prescriptions of the secret key whereby the locking rod and the rotatable bolts are adjusted to the open position.

25 When the lock is open said two parts are rendered immovable so that the caps g alone can be rotated in overcoming the resistance of spring m and in pressing back the locking pins l to be adjusted to a new secret number. As the marks n are provided on 30 the rotatable bolts which at the open position must always adopt the same position the last adjusted secret number will always appear when the lock is being opened even if the caps have been rotated in the meantime.

35 I claim:—

40 1. A combination lock comprising in combination a **U**-shaped bow, a locking bolt designed to lock the free ends of the arms of said **U**-shaped bow, a locking rod in the lower arm of said **U**-shaped bow designed to lock said locking bolt, rotatable bolts cooperating with said locking rod, round heads one for each rotatable bolt, a cap of 45 polygonal cross section on each rotatable bolt, and releasable means in said heads of the rotatable bolts for locking the same in position in the corresponding caps.

50 2. A combination lock comprising in combination a **U**-shaped bow, a locking bolt designed to lock the free ends of the arms of said **U**-shaped bow, a locking rod in the lower arm of said **U**-shaped bow designed to lock said locking bolt, rotatable bolts cooperating with said locking rod, round

55 heads one for each rotatable bolt having a transverse bore, a cap of polygonal cross section on each rotatable bolt, two locking pins with conical outer ends movably mounted in the transverse bore of each head of each rotatable bolt and a spiral spring located in said bore between said two locking pins to push the same in outward direction and to bring the conical ends in engagement with the inner surface of the corresponding cap.

60 3. A combination lock comprising in combination a **U**-shaped bow, a locking bolt designed to lock the free ends of the arms of said **U**-shaped bow, a locking rod in the lower arm of said **U**-shaped bow designed to lock said locking bolt, rotatable bolts cooperating with said locking rod, round heads one for each rotatable bolt, a cap of 65 polygonal cross section on each rotatable bolt and releasable means in said heads of the rotatable bolts for locking the same in position in the corresponding caps, an adjusting handle in the outer end of said locking rod and a mark on the outer surface of said adjusting handle, said mark being designed to indicate the open position of the elements of the lock.

70 4. A combination lock comprising in combination a **U**-shaped bow having an aperture in the end of its upper arm and an angular groove in the lower surface of said upper arm, a locking bolt designed to lock the free ends of the arms of said **U**-shaped bow, a locking rod in the lower arm of said **U**-shaped bow designed to lock said locking bolt, rotatable bolts cooperating with said locking rod, round heads one for each rotatable bolt, a cap of polygonal cross section 75 on each rotatable bolt and releasable means in said heads of the rotatable bolts for locking the same in position in the corresponding caps, a pull spring located in said upper arm of the **U**-shaped bow, a chain attached with one end to said locking bolt and with the other end to said pull spring, said pull spring being designed to pull said bolt when it has been released at first in upward direction, then to oscillate it through 90° in said 80 aperture at the front end of the upper arm of the **U**-shaped bow and to pull it back finally in horizontal direction, all these movements being executed automatically at the releasing of the locking bolt.

85 In testimony whereof I affix my signature in presence of two witnesses.

KARL WÖRTMANN.
